UNITED STATES PATENT OFFICE.

OTTO PETERMANN, OF GROTON, NEW YORK, ASSIGNOR TO CORONA TYPEWRITER COMPANY, INCORPORATED, A CORPORATION OF NEW YORK.

CARRIAGE FOR TYPE-WRITING MACHINES.

1,162,507.

Specification of Letters Patent.

Patented Nov. 30, 1915.

Application filed September 15, 1910. Serial No. 582,215.

To all whom it may concern:

Be it known that I, OTTO PETERMANN, a citizen of the Republic of Switzerland, and a resident of Groton, county of Tompkins, 5 and State of New York, have invented certain new and useful Improvements in Carriages for Type-Writing Machines, of which the following is a full, clear, and exact description.

10 This invention relates more particularly to means for adjustably holding the paper fingers which fit about the platen.

The primary object of the invention is to provide simple and efficient means for supporting and adjustably holding the paper fingers whereby the said fingers may be quickly moved and properly held in their new positions without detaching any of the parts or releasing screws or similar fastening means, thus greatly facilitating the adjustment of the paper fingers to different widths of work and avoiding many of the objections incident to the use of the usual holding means for such devices.

20 Another object of the invention is to provide means whereby one of the paper fingers may be utilized to have the cord of the tension or propelling mechanism attached thereto.

30 A further object of the invention is to provide simple and efficient holding means for the paper fingers which may be readily made and which may be applied to various forms of typewriting machines.

35 With these and other objects in view, the invention will be hereinafter more particularly described with reference to the accompanying drawings, which form a part of this specification, and will then be pointed out in the claims at the end of the description.

In the drawings, Figure 1 is a rear elevation of the carriage and support of one form of typewriting machine with my invention applied thereto. Fig. 2 is a transverse section through the platen, showing the means for adjustably supporting one of the paper fingers about the platen. Fig. 3 is a plan view; and Fig. 4 is a detail perspective view 50 of the paper finger holding means and part of the supporting bar.

The bed 10 may have a carriage 11 adapt-

ed to move lengthwise thereof, and supported on a carriage is a suitable platen 12, all of which may be of the usual or of any 55 preferred construction.

The carriage frame has end pieces 13 and 14, and held to these end pieces so as to extend lengthwise of the platen 12, is a bar 15. This bar 15 is preferably square or rectangular in cross-section and is held in any suitable way and in any desired location on the carriage 11. As shown, the ends of the bar are reduced and fit in slots in the ends 60 13 and 14 of the carriage frame at the rear 65 thereof and said bar is held between the ends of said frame by the screws 16.

A device 17 is arranged on the bar or support 15 at one end thereof, and a device or holder 18 is arranged at the other end of 70 said support 15. These devices each have a member 19 and this member has an upright portion 20 provided with a substantially U-shaped head 21 through which are square openings 22 of substantially the 75 same size as the bar or support 15. The head has two sides 23 which are spaced apart so as to give sufficient bearing surface on the bar to be properly guided thereon, and each side 23 has one of the openings 22, 80 and movable relatively to the guiding member 19 is a clamping member 24. The clamping member 24 has a spring part 25 which is secured to the member 19 by a screw 26 or otherwise, and has a substantially U- 85 shaped head 27, the side walls 28 and 29 of which are adapted to fit about and be guided by the side walls 23 of the head 21, and one of the side walls 28 and 29 of the member 24, as wall 29, has an opening 30 90 somewhat larger than the bar 15. One edge of the opening 30 of the side wall 29 serves as an engaging portion or dog 31, and this dog is adapted to enter slots 32 formed in the bar at one side thereof. The member 24 95 may be of spring material and is normally forced away from the member 19 to cause the dog 31 to enter one of the slots 32. This will hold the device against lengthwise movement along the bar, but by forcing the 100 member 24 inward to remove the dog 31 from engagement with one of the slots 32, the entire device may be moved along the bar, and as soon as the member 24 is re-

leased, the dog will engage one of the slots and hold it against further movement until again released.

The members 19 and 24 have a projecting part 33 of the paper finger 34 held between the same, and this part of the paper finger may be held between these members by the fastening screw 26, and each paper finger has a curved part 35 which is adapted to 10 pass under and about the platen 12. The head 27 of the member 24 at the rear thereof may be concaved, as at 36, to adapt a finger of the operator to rest easily thereon, and said concaved portion may be roughened to 15 prevent the operator's finger slipping. A spring 36^a may be interposed between the part 33 of the paper finger and the rear part of the head 27 tending normally to force the dog 31 into engagement with one of the slots 20 32. The spring 36^a may be dispensed with and the member 24 made of spring material, or the spring 36 may be employed whether the member 24 is made of spring material or not. By this means, a very simple construction is provided and all that is necessary is for the operator to use his fore finger to press against the part 36 which will release the dog 31 from engagement with the slots, and as the same is pressed, the entire 25 30 device with the paper finger carried thereby may be quickly and easily moved to any desired position for different widths of work.

One of the devices, as the device 17 for example, may have the stem portion extended downward, as at 37, and to this downwardly-extending portion may be connected the cord or connection 38 of the tension or propelling mechanism for forcing the carriage along the bed, in which case the 35 40 other device 18 need not be extended, though it will be understood that the cord may be connected to any other part of the carriage if desired.

The devices 17 and 18 are similarly constructed except for the stem extension 37 of the device 17, and each device besides carrying a paper finger is adapted to engage the edge 38^a of the bracket or stop 39. The bracket 39 is fixed to the carriage bed 10 50 and may serve as a guide for the carriage to assist in holding said carriage to the bed as it travels back and forth along the same in the usual way. The devices 17 and 18 thus act to limit the extent of the movement 55 of the carriage along its bed in either direction as well as carriers for the paper fingers.

From the foregoing it will be seen that simple and efficient means are provided 60 whereby the paper fingers may be readily supported and quickly adjusted and held in their adjusted positions; that said means may be readily and easily made; and that one of the paper finger supporting devices 65 may be utilized to have the connection for

the tension mechanism attached thereto for forcing the carriage along the bed when released by the escapement mechanism.

Having thus described my invention, I claim as new and desire to secure by Letters Patent:—

1. The combination with a support having a plurality of slots, of a plurality of devices held upon said support, each of said devices comprising two relatively movable members, said members attached to each other at one point and having heads located away from the point of attachment and having one head fitting about and slidable upon the exterior surface of the other, and one of which heads has means adapted to engage the slots of the support and hold the device against movement until released, a platen, and paper fingers carried by said devices and extending about said platen. 85

2. The combination with a support having a plurality of slots, of a plurality of devices held upon said support, each of said devices comprising two relatively movable members, said members having substantially 90 U-shaped heads one fitting about and slidable upon the exterior surface of the other, and one of which has an integral dog adapted to engage the slots of the support and lock the device against movement until released, a platen, and paper fingers carried by said devices, and extending from the rear of the 95 machine forward about the platen.

3. In a typewriting machine, the combination of a carriage, a platen mounted in said carriage, a support, a device adjustably held on said support and having two members each provided with pendent portions, and adapted to slide one upon the other, means for holding the pendent portions of the 100 members together to adapt one member to swing toward or away from the other, one of said members having means to lock the device in its adjusted position along said support, and a paper finger extending forward from the device and adjustable therewith and adapted to fit about the platen. 110

4. In a typewriting machine, the combination of a carriage, a platen mounted in said carriage, a support, a device adjustably held on said support and having two members provided with overlapping heads adapted to slide one upon the other, and having parts projecting from said heads and permanently attached together to adapt one member to 115 swing toward or away from the other, and a paper finger carried by the device and adjustable therewith. 120

5. In a typewriting machine, the combination of a carriage, a platen mounted on said carriage, a support, a device adjustably mounted on said support and having two members joined together at a point away from the support to adapt one member to move relatively to the other and normally 125 130

engage and be locked to said support or be disengaged therefrom by pressure of the operator's finger, and a paper finger mounted on said device and adapted to extend about the platen.

5 6. In a typewriting machine, the combination of a carriage, a platen mounted on said carriage, a support, a device adjustably mounted on said support and having members yieldingly joined together at a point away from the support to adapt one member to move relatively to the other and normally engage and be locked to said support or be disengaged therefrom by pressure of the 10 operator's finger, and a paper finger mounted on said device and adapted to extend about the platen.

15 7. In a typewriting machine, the combination of a carriage, a platen mounted in said carriage, a support, a device mounted on said support and having two relatively movable and overlapping plate-like members provided with substantially U-shaped heads fitting about each other, yielding means 20 tending normally to separate said members, and a paper finger carried by said device.

25 8. In a typewriting machine, the combination of a carriage, a platen mounted in said carriage, a support, a device mounted on said support and having relatively movable and overlapping plate-like members provided with substantially U-shaped heads fitting about each other, and with pendent portions permanently attached together, 30 yielding means tending normally to separate said members, and a paper finger carried by said device.

35 9. In a typewriting machine, a substantially rectangular supporting bar having vertical slots on one side thereof, a device 40 having a member provided with an elongated body portion and a substantially U-shaped head having slots fitting about the bar and slidable lengthwise thereof, a second member having a head, one part of which is provided with a slot larger than the cross section of the bar to adapt the said second member to move relatively with regard to the first mentioned member, said 45 second member having a portion secured to the body portion of the first-mentioned member and forming a spring connection therewith, said second member also having a depressed part for the finger of the operator to 50 adapt the members to be moved relatively with respect to each other to adapt the device to be moved readily along its supporting bar, and a paper finger extending forward and upward about the platen to hold 55 the work sheet about the same.

60 10. In a typewriting machine, a supporting bar having slots, a device having a member provided with an elongated body portion and a substantially U-shaped head having slots fitting about the bar and slidable

lengthwise thereof, a second member having a part provided with a slot larger than the cross section of the bar to adapt the said second member to move relatively with regard to the first-mentioned member, said 70 second member having a depressed part for the finger of the operator to adapt the members to be moved relatively with respect to each other to adapt the device to be moved readily along its supporting bar, and a paper finger extending about the platen to hold the work sheet about the same.

75 11. The combination with a rectangular supporting bar, of a device having two relatively movable members, one of which has a substantially U-shaped head provided with openings through which the bar passes and serving as a guiding member, and the other member having an integral spring connection with the guiding member and having 80 a substantially U-shaped head adapted to span the said guiding member and the support, and provided with means to engage the bar to permit the device to be adjusted along said bar, a platen, and a paper finger 85 mounted upon the device and extending about the platen.

90 12. In a typewriting machine, a substantially rectangular supporting bar having vertical slots on one side thereof, a device 95 having a member provided with an elongated body portion and a substantially U-shaped head having slots fitting about the bar and slidable lengthwise thereof, a second member having a substantially U-shaped head, one part of which is provided with a slot larger than the cross section of the bar to adapt the said second member to move relatively with regard to the first mentioned member, said second member having 100 a portion secured to the body portion of the first-mentioned member and forming a spring connection therewith, said second member also having a depressed part for the finger of the operator to adapt the members to be moved relatively with respect to each other to adapt the device to be moved readily along its supporting bar, a spring 105 interposed between the heads of the two members, a platen, and a paper finger carried between the two members and projecting upward between the heads and curved so as to fit about the lower portion of said platen.

110 13. The combination with a supporting 120 bar, of a device mounted on each end of the bar and comprising two members one of which has a head provided with openings adapted to fit about the bar and form a guiding member, and the other made of 125 spring material and having a head which is relatively movable with respect to the head of the guiding member and has a part thereof provided with an opening to form an engaging portion adapted to enter the 130

slots of the bar, a spring interposed between the two members normally moving the heads of the two members away from each other, means whereby the second member may be moved to release the same from the bar, a platen, and a paper finger carried by each device and extending about the platen.

14. The combination with a supporting bar, of a device mounted on each end and comprising two members one of which has a head adapted to fit about the support and serve as a guiding member, and the other also having a head which is relatively movable with respect to the head of the guiding member and has a part thereof provided with an opening to form a portion adapted to enter the slots of the bar, a spring interposed between the two members normally moving the heads of the two members away from each other, a platen, a paper finger mounted on each device and extending about the platen, and means whereby the engaging member may be moved to release the same from the bar, one of said devices having an

extended part to which the carriage tension means may be attached.

15. The combination with a bar, of a device mounted on said bar and comprising two members one of which has a head provided with openings adapted to fit about the support and serve as a guiding member, and the other also having a head which is relatively movable with respect to the head of the guiding member and has a part thereof provided with an opening to form a portion adapted to engage the bar, one of said devices having an extended portion for the attachment of a part of the carriage tension mechanism, a platen, and a paper finger mounted on said device and extending about the platen.

This specification signed and witnessed this 12th day of September A. D. 1910.

OTTO PETERMANN.
